[57] **CLAIM**

The ornamental design for a clamp for pegboard hook, as shown and described.

DESCRIPTION

FIG. 1 is a top, front and left side perspective view of a clamp for pegboard hook showing my new design;
FIG. 2 is a bottom plan view thereof;
FIG. 3 is a left side elevational view thereof, with the right side constituting a mirror-image of the left side; and,
FIG. 4 is a rear elevational view thereof.
